UNITED STATES PATENT OFFICE.

EMANUEL C. GIPE, OF FREEPORT, ILLINOIS, ASSIGNOR OF THREE-FOURTHS
TO GEORGE W. TASSELL, OF WAUKESHA, WISCONSIN, AND FELIX J. GRIF-
FEN, OF CHICAGO, AND HENRY L. GLOS, OF ELMHURST, ILLINOIS.

CASH AND PACKAGE CARRIER.

SPECIFICATION forming part of Letters Patent No. 623,899, dated April 25, 1899.

Application filed May 23, 1898. Serial No. 681,458. (No model.)

To all whom it may concern:

Be it known that I, EMANUEL C. GIPE, of Freeport, in the county of Stevenson and State of Illinois, have invented certain new and useful Improvements in Cash and Package Carriers, of which the following is a full, clear, and exact description, reference being had to the accompanying drawings, forming a part of this specification, in which corresponding letters of reference in the different figures indicate like parts.

My invention relates to that class of package-carriers in which a suitable basket or receiver is detachably connected with a car adapted to roll upon a suspended wire or rod, said device being provided with means whereby the basket may be raised or lowered by the operator at either end of the line and locked to or released from the car through the action of suitable automatic mechanism; and the object of my invention is, among other things, to so arrange and construct said mechanism that by pulling upon a given cord connected with a stirrup adapted to suspend the basket while being raised or lowered the basket may, by the same movement of the stirrup, be alternately released from and locked to the car.

Other objects are to provide simple automatic means for locking the car to and releasing the same from the bumpers, to provide simple and novel means for suspending the basket below but out of contact with the car when not in use, for holding the releasing-stirrup in a given normal position, and in providing improved means for guiding and controlling the propelling mechanism, all of which is hereinafter more particularly described, and definitely pointed out in the claims.

In the drawings, Figure 1 is a side view of a package-carrier mechanism embodying the features of my invention. Fig. 2 is a plan view thereof. Fig. 3 is an enlarged detailed view of a portion of the left-hand end of said carrier mechanism, said view being partly in section. Fig. 4 is a central vertical longitudinal sectional view in detail of a part of the locking mechanism, showing the same in a

locked position, said view being taken upon line 44, Fig. 7. Fig. 5 is a similar view showing the parts as they would appear in an unlocked position. Fig. 6 is a like view showing the parts as they would appear when the basket is about to be locked to the car. Fig. 7 is a transverse vertical sectional view in detail of the stirrup mechanism for locking the basket to and releasing it from the car, together with means for normally controlling said stirrup and holding the same in a disengaged position. Fig. 8 is a plan view in detail of the plate from which the basket is suspended and which serves to connect the same with the car; and Fig. 9 is a view of the parts shown in Figs. 5 and 6, but representing them in slightly-different relative positions.

Referring to the drawings, *a* and *b* respectively represent the usual vertical standards, which are rigidly attached to the ceiling in any suitable manner. Attached to the lower end of the standard *a* is a sleeve *c*, having lugs *d d* formed thereon, whereby to connect the usual diagonal braces *e e*, which are in turn secured to the ceiling. An arm *f* is extended forward from the sleeve, and serves not only as a means for anchoring one end of a wire *i* thereto, but a cross-bar *g*, Figs. 2 and 7, secured thereon serves as a means for supporting pulleys *s' s'* and other parts, which will be hereinafter described. The standards *b b*, consisting of parallel bars, are secured in a similar manner to that of the standard *a*, and are braced by means of diagonal braces *b' b'*, which are attached to the opposite ends of a cross-bar *b*. The latter is bolted between flanged plates *b*, Figs. 1, 2, and 3, formed upon the lower end of said bars. Depending from the bottom plate *b* are two parallel flanges *b*, which lie in the same planes, respectively, with those of the standards *b*. Between said flanges, as well as between the lower ends of the standards *b*, are mounted winches *h h*, Fig. 3, to which are attached ratchet-wheels *h' h'*, controlled by pawls *h' h'*, as shown. Wires *i j* are attached to the winches, respectively, which may be tightened in the usual manner by means of a suit-

able key. The wires are passed through bores, as shown in cross-pieces $i' j'$, by which said wires are maintained in the same vertical plane. A rod l (better shown in Fig. 3) is projected loosely through a bore in a cross-piece k at the bottom of the flange b^5 . To the opposite end of the rod is attached a combined bumper and catch m , having an upwardly-extended arm m' , through which the wire j is loosely passed, thus serving to support said bumper and to hold the same in alinement with the wires. Spiral springs $l' l^2$ are mounted upon the rod l , upon opposite sides of the plate k , to enable the part m to act as a buffer.

The opposite end of the wire i is passed through a bore in a lug g , Fig. 7, and fastened to a pin f' upon the arm f . The rod j is passed through a bore in the fitting upon the lower end of the standard a and is permanently attached thereto. A bumper m^2 is secured to said fitting and connected to the wire j in the same manner that the bumper m is connected at the opposite end. It will thus be seen that the wires $i j$ are in the same vertical plane throughout their length, the object of the former wire being to simplify the framework by supporting the forward pulleys and other parts of the propulsion mechanism hereinafter described. Clamped to the wire i in the manner indicated in Figs. 1 and 2 are cross-bars $n o$, provided with depending arms $o' n'$, to which are attached pulleys $n^2 n^2 o^2 o^2$, the axes of which are in substantial alinement with the wire j .

Mounted upon the wire j are wheels $p p$, from which is suspended the frame q of a car adapted to be propelled upon the wire by means of an impulse, as hereinafter described. Pivoted to the opposite ends of the car are catches $r r$, which are held in normal positions, respectively, by means of a spring r^3 , Fig. 3. Each of said catches is provided with a part r^2 , which passes over the wire j , the oscillatory movement being limited in both directions by suitable stops adapted to engage the end of the car. A bar r' , which connects downwardly-inclined parallel arms of said catch, serves to engage and interlock with the bumper m in the manner clearly indicated in Fig. 3, a roller being mounted upon said bar to lessen the friction as it rides up upon the incline m^3 .

The propelling mechanism at the transmitting-station is as follows: An arm s , Figs. 1 and 2, is rigidly attached to the standard a and is extended rearwardly therefrom. Upon the standard a is mounted a pulley s' and upon the arm s a secondary pulley s^2 . A cord s^3 has one end attached to a snatch-block s^4 , thence over the pulley s^2 through the snatch-block, over the pulley s' , around one of the pulleys n^2 , thence rearwardly around the catch r of the car, forward to and around the second pulley n^2 , thence back over the pulley s' through the snatch-block, thence around the pulley s^2 and back to the snatch-

block, to which it is attached. A cord t enables the snatch-block to be actuated by the operator. A rod t' , Fig. 1, is rigidly attached to the snatch-block at one end and pivotally attached to the cross-bar n at the other, and thus serves as a guide in directing and steadyng the movement of the snatch-block and in preventing the latter from swaying unduly, as it is liable to do without this device. By the arrangement described of the cord-and-pulley mechanism, in conjunction with the spring-catches r , the car is released from its connection with the bumper, the initial strain upon the cord serving to lift the catch r , and is propelled with the requisite speed and force along the wire j to the receiving-station, where the catch r upon the opposite end of the car is brought into engagement with the bumper and automatically locked thereto. In the meantime it is brought into engagement with the propelling-cord u at the receiving-station, which is in contact with the catch r , as shown in Fig. 3, ready to release and impart a backward impulse to the car.

At the receiving-station there is provided a snatch-block v , having a handle v' thereon, and the cord u is trained from said snatch-block over a pulley u' , supported by the standard-bars b , thence beneath the pulley v of the snatch-block, thence over a pulley u^2 upon an arm u^3 , thence over one of the pulleys o^2 , beneath the wire j , over the other pulley o^2 back to the pulley u^2 , through the snatch-block v , over the pulley u' , and back to the snatch-block, to which it is attached. A rod v^2 like the rod t' is rigidly attached to the snatch-block v and pivotally to the cross-bar o . Said rod passes between the vertical bars b , which thereby form guides to prevent any lateral movement of the rod and enables the propelling mechanism to be operated with the utmost smoothness and ease. By the use of my improved propelling mechanism, including the series of pulleys, the speed is greatly increased.

In Figs. 4 to 8, inclusive, I have shown my improved mechanism for locking the basket to the car and releasing the same therefrom. The usual basket w , which is represented in Fig. 1, is provided with suspending-wires w' , shown in the figures last above referred to, which wires are clamped at the top to a locking-plate w^2 . Openings are formed in the plate, leaving a central cross-bar w^3 , which is adapted to engage the lock. Pivoted at q' in the frame q is an oscillatory knuckle q^2 , having detents q^3, q^4 , and q^5 , for the purposes hereinafter stated. A retaining-dog x is also pivoted within the frame at x' and is preferably provided with the spring x^2 , by which to force the free end downwardly. A trigger x^3 is pivotally attached to the end of the dog x , while a spring x^4 is attached to the dog and arranged to bear upon the square end of the trigger. The latter is thus held in a normal position with relation to the dog x , while at the same time it is free to yield therefrom in

either direction in the manner hereinafter stated. Guides q^6 extend downwardly from the bottom of the car, the same being provided with inclined converging faces q^7 , which are adapted to engage the cross-bar w^3 when the latter is lifted and to guide it into contact with the knuckle q^2 . Pulleys s^5 are supported upon cross-arms and arranged upon opposite sides of the bar s , and similar pulleys s^7 are mounted upon the cross-bar g' , (better shown in Fig. 7,) beneath which are secured vertically-arranged tubes g^2 g^2 , containing spiral springs g^3 . Cords s^6 are trained over the pulleys s^5 s^7 and extended downwardly through the tubes g^2 , and upon the protruding ends of said cords are attached acorn-shaped bulbs s^8 s^8 , which are adapted to engage the lower ends of the spiral springs g^3 when the cords are drawn upwardly. Attached to the bulbs s^8 are short chains, as shown, which are connected with a stirrup y , which hangs normally at such a height, as shown in dotted lines in Fig. 7, as to permit the part q^6 of the car to freely pass thereover. The plate w^2 is notched inwardly, as shown at w^4 w^4 , Figs. 7 and 8, so that when the basket is suspended from the car and the latter is moved to its initial position the chains or arms of the stirrup are received into the notches w^4 , thus leaving the stirrup y immediately below the cross-bar w^3 , as indicated in dotted lines in Fig. 4. The notches w^4 are enlarged at their inner ends, as shown at w^5 w^5 , to receive the parts y' of the stirrup. By means of this construction the plate w^2 and stirrup are practically locked to each other as long as the two are in the relation specified, and hence the shaking of the basket will not cause it to become disconnected therefrom.

Attached to the rear end of the arm s is a vertical rod z , which extends downwardly therefrom and is provided with a bend z' near the upper end, which is substantially at right angles thereto, and a bend z^2 in an opposite direction at the bottom. The bends z' z^2 respectively form arms or stops for the engagement of a loop s^9 upon the cords s^6 , which are thus brought together and provided with the usual handle s^{10} , which enables the operator to raise and lower the basket. Inasmuch as it is not desirable to raise the basket and lock it to the car each time after its return from the wrapper's desk until it again becomes necessary to use it I employ the bar z , with the arm z' z^2 , the latter being used from which to suspend the basket normally out of the way. By releasing the loop s^9 from the arm z^2 and catching it upon the arm z' the basket may be lowered to the desired height for loading.

Having thus described the various parts of my improved device, I will now explain its operation. The basket being loaded, the operator pulls upon the cord s^6 , from which the basket is suspended, as shown in Fig. 1, until the bar w^3 of the plate w^2 is brought into con-

tact with the detent q^4 of the knuckle q^2 , which is in the position shown in Fig. 5. By lifting the basket until the plate w^2 is in contact with the bottom of the car the part q^5 of the knuckle is thrown back, so as to permit the dog x to fall, thus engaging the detent q^5 with a shoulder x^5 upon said dog and locking the knuckle positively in position, as shown in Fig. 4, when the detent q^3 is thrown beneath the bar w^3 , which is thereby securely locked to the car. By the action of the dog x , the free end of which moves in the arc of a circle, the lower end of the trigger x^3 is thrown against a flange, as shown, upon one side of the stirrup y , but is permitted to yield through the action of the spring x^4 to allow the stirrup y to fall into its normal position as soon as the tension is released upon the cord. The recoil of the springs g^3 , which are in engagement with the parts s^8 when the stirrup is raised, serves to overcome the weight of the handle s^{10} and to lower the stirrup, thus leaving the car free to pass over it without contact. The car is then propelled to its destination in the manner and by means of the propelling mechanism hereinbefore described and returned to the sender's station. Upon the return of the car to the transmitting-station the operator again pulls upon the handle s^{10} , lifts the stirrup into contact with the trigger x^3 , which has been thrown into position to engage the stirrup by the action of the spring x^4 , (see Fig. 4,) and the trigger being raised lifts the dog x and releases the detent q^5 from contact therewith. The weight of the basket serves to move the part q^2 into the position shown in Fig. 5 and the basket is free to be lowered. It will be observed that the stirrup y is notched, as shown at y^2 , Fig. 4, which notch engages the end of the trigger and holds it in contact with the stirrup until the latter is raised to its full height. This action is permitted by the yielding of the pivoted trigger, the end of which would, when raised to a given height, slip off from the stirrup and fall back, thereby defeating the purpose intended. As soon, however, as the stirrup is lowered the spring acting upon the upper end of the trigger causes it to assume the position shown in Fig. 5, so that when it is desired to reengage the bar w^3 with the knuckle the stirrup may be lifted up to the full limit without engaging the trigger, as shown in Fig. 6. It will thus be seen that my improved locking mechanism is so constructed that a given upward movement of the stirrup may serve to release the basket from the car, while the next upward movement thereof serves to lock it. The advantages of this feature are too obvious to require mention.

Having thus described my invention, I claim—

1. In a package-carrying mechanism the combination with a car and a detachable basket and a suspending locking-bar attached to the basket, of a locking mechanism consist-

- ing of an oscillatory toothed knuckle adapted to be engaged by said suspending locking-bar, a dog for holding said knuckle in either of two extreme positions, a stirrup for raising 5 and lowering said basket in a path to bring said locking-bar into contact with the knuckle, and a releasing-trigger constructed to lie in the path of movement of the stirrup when the parts are in locked positions and out of said 10 path when they are reversed, whereby the same movement may serve to alternately release the basket from or lock the same to the car, substantially as described.
2. In a package-carrying mechanism, the 15 combination of a car, a detachable basket and a locking mechanism consisting of an oscillatory pivoted knuckle having a series of detents thereon, a pivoted dog for maintaining said knuckle in one of two extreme positions, 20 a trigger for lifting said dog when in a locked position, a cross-bar attached to the basket for engaging said knuckle and a stirrup adapted to engage said trigger when the parts are in locked positions respectively, substantially 25 as described.
3. In a package-carrying mechanism, the combination with a car and a detachable basket and a suspending locking-bar attached to the basket, of a locking mechanism consisting 30 of an oscillatory toothed knuckle adapted to be engaged by said suspending locking-bar, a dog for holding said knuckle in either of two extreme positions, a stirrup for raising and lowering said basket in a path to bring 35 the locking-bar into operative contact with the knuckle, means such as the springs g^3 and bulbs s^8 for normally holding said stirrup out of contact with the car, and a releasing-trigger constructed to lie in the path of movement 40 of the stirrup when the parts are in locked positions and out of said path when they are reversed, substantially as described.
4. The combination with a car and a detachable basket of an automatic locking mechanism in which is combined a suspending 45 locking-bar upon the basket, an oscillatory toothed knuckle adapted to engage said bar, a dog for holding said knuckle in one of two extreme positions, a yielding trigger provided 50 with means for holding the same in a normal relation with respect to the dog but to permit the same to yield when force is applied thereto, and a stirrup in operative connection with the
- basket-suspending cords, said stirrup being arranged to engage said trigger only when the latter is in one of two extreme positions, substantially as described. 55
5. The combination with a car and a detachable basket of the plate w^2 having notches w^4 a stirrup adapted to be suspended from the operating-cords, in alignment respectively with said notches, said stirrup being provided with the parts y' adapted to engage the notches in said plate when the basket is suspended therefrom suitable locking mechanism and 60 means for releasing the same through the operation of said stirrup, substantially as described. 65
6. The combination in a mechanism of the class described of a movable car, a detachable basket, cords for raising and lowering said basket to and from the car and a depending rod having horizontal arms extending therefrom at predetermined distances whereby the suspending-cord may be hooked thereto and 70 the basket suspended at different heights 75 without locking the same to the car, substantially as described.
7. In a mechanism of the class described, the combination with a car and a detachable basket, of propulsion-cords trained over pulleys and in operative connection with the car, a secondary wire, a snatch-block and a rod pivoted to the snatch-block and to said secondary wire at a point above the track-wire 85 and forward of the normal position of the car, substantially as described. 80
8. In a mechanism of the class described, the combination with a car and a detachable basket, of propulsion-cords trained over pulleys and in operative connection with the car, of a secondary wire, a snatch-block, a rod pivoted to the snatch-block and to a point upon said secondary wire above the track-wire, said pivotal point being between the two stations, 90 and guides for preventing a lateral movement of said rod when the propulsion mechanism is operated, substantially as described. 95
